UNITED STATES PATENT OFFICE.

HERMAN J. ZOTTEL, OF MILWAUKEE, WISCONSIN.

LOCK NUT.

1,426,530.

Specification of Letters Patent. Patented Aug. 22, 1922.

Application filed April 25, 1919. Serial No. 292,569.

To all whom it may concern:

Be it known that I, HERMAN J. ZOTTEL, a citizen of the United States, residing at Milwaukee, county of Milwaukee, State of 5 Wisconsin, have invented certain new and useful Improvements in Lock Nuts, of which the annexed is a complete, concise, and clear specification, reference being taken to the accompanying drawing, which 10 forms part of this specification.

My present invention is an improvement upon the nut lock patented by me December 19th 1916, the patent number of which is 1,209,302.

15 The object of this invention is to provide means indicating to the user of my lock nut when same is properly locked.

In the nut lock covered by the above patent, as well as in all other known types 20 of nut locking means, reliance is placed solely upon the judgment of the mechanic applying the same, as to what constitutes the proper tension for securely locking the nut in place.

25 This frequently leaves the lock nut insecurely locked, while in other cases it may be turned beyond the proper tension, thereby doing damage to the bolt threads.

Another object of this improvement is 30 to facilitate the manufacture of my lock nut. To obtain the required resiliency in the locking prongs it is necessary to shear the metal clear through for the entire length of the prongs. The metal will not 35 break until the punch has cut through about two thirds its thickness. Therefore when producing the device covered by the above patent, it was found necessary to shear the metal beyond the proper depth in 40 order to separate the prongs from the solid plate their entire length to render them sufficiently resilient and later force them back to the desired shape. One of the objects of the present improvement is to so 45 shape the prongs that the shearing operation in itself produces the desired shape, whereby a subsequent forming of the prongs is eliminated, and yet shearing them free from the plate their entire length.

50 The particular method by which the above objects are obtained will be more specifically described with reference to the annexed drawing, of which Fig. 1 is a top view of the lock nut; Fig. 2 is an end view 55 thereof; and Fig. 3 shows the application

of the lock nut when in the locked position.

Referring to Figs. 1 and 2, character 6 shows the flat plate of the lock nut, which may assume the outer contour shown, or any other suitable shape. Characters 7 and 60 8 show three prongs or wings formed by shearing the plate at characters 7, severing a portion of the material of the plate by suitable arcuate cuts and abruptly bending 65 the prongs at characters 8 to the desired form. Character 9 shows the threaded bolt opening.

It will be observed from Fig. 2 of the drawing, that the prongs are formed to present a slight incline to the plane of the plate, which is more clearly shown by the two broken lines and the angle X. It will be noted that the prongs are sheared so the free ends thereof, characters 7, are depressed the greater extent, while the attached ends thereof, characters 8, are depressed a lesser extent. 70 75

Before the lock nut is tightened into locking position, the screw thread therein 80 is normal, that is, the lock nut can be freely moved upon the thread of the bolt. And the appearance of the lock nut is as illustrated by Fig. 2, with the prongs at the angle X to the plane of the plate. 85

If the lock nut is now tightened into locking position with a wrench, the free ends of the prongs, characters 7, are forced back until the attached ends thereof, characters 8, contact with the face of the primary nut. 90

The angle X is of such magnitude, that the lock nut is properly and securely locked when this angle is zero. This condition is more clearly shown in Fig. 3, the prongs 95 contacting substantially with their entire length with the face of the primary nut.

When this condition is reached, the mechanic will feel a very sudden and decided increase in the resistance offered by the lock 100 nut against further turning. After the prongs are flattened, the sharply bent portions, characters 8, come to bear against the face of the primary nut, and as these portions are not resilient or movable with respect to the solid plate of the lock nut, a substantial stop against further turning is 105 effected.

This removes all uncertainty on the part 110 of mechanics and users, and the operation

of applying the lock nuts is performed with materially increased dispatch.

It will therefore be apparent that the features of this improvement are of material value, both in the manufacture of the lock nuts and in their application.

While the drawing shows my lock nut used in connection with a primary nut, it will be evident that the primary nut may 10 be dispensed with. The lock nut then serves for holding as well as locking purposes. This applies particularly to the smaller sizes.

Variations in the details and construction of my lock nut are readily effected by those skilled in the art, but these will be considered as within the scope of this application. What I claim as new and my invention, is more specifically covered by the 20 following claims:

1. A lock nut comprising a plate with a threaded bolt hole and locking pawls

integral therewith, the locking pawls being formed by cutting from the plate a portion of the material adjacent the bolt hole and sharply depressing the same at the attached end thereof, so that the free end of the locking pawls is rendered readily compressible while the attached end thereof is comparatively incompressible.

2. A lock nut comprising a plate with a threaded bolt hole and locking pawls integral therewith, the locking pawls being formed by cutting from the plate a portion of the material adjacent the bolt hole, sharply offsetting the same at the attached end thereof and depressing the free end to a greater depth than the attached end.

In witness whereof, I hereunto subscribe my name this 22nd day of April A. D. 1919.

HERMAN J. ZOTTEL.
